(57) **CLAIM**

The ornamental design for a coaxial connector with slotted hexagonal nut, as shown and described.

DESCRIPTION

FIG. 1 is a perspective view of the coaxial connector with slotted hexagonal nut of the present invention;

FIG. 2 is a top plan view thereof;

FIG. 3 is a side elevational view thereof;

FIG. 4 is a bottom plan view thereof;

FIG. 5 is a side elevational view thereof; and,

FIG. 6 is a perspective view thereto.

The broken line portion of the figure drawings is included to show unclaimed subject matter only and forms no part of the claimed design.
